FIREARM

Charles H. Barnes, Nichols, Conn., assignor to
Remington Arms Company, Inc., a corporation
of Delaware

Application July 1, 1939, Serial No. 282,368

4 Claims. (Cl. 42—22)

This invention relates to firearms and particularly those of the pump action type but is not limited thereto.

Pump action firearms may be described generally as being those in which a reciprocating operating handle for giving the motion necessary to unlock the breech mechanism, retract the breech bolt, eject the fired shell, cock the hammer, deliver a fresh shell from a magazine to the chamber and lock the parts again in closed position, is guided on suitable means held substantially parallel to the barrel.

One of the objects of the invention is the provision of means to facilitate removal of the fired cartridge case from the chamber, especially to assist in the initial movement thereof and also to assist in the closing action. The pressure developed in the case upon firing often expands the same, causing the case to stick in the chamber. Another of the objects is the provision of a box magazine that may be easily inserted and held in position and a simplified construction of the holding means.

The means to facilitate removal of the fired cartridge case and to assist closing action may be used however with any type of cartridge feeding mechanism and the magazine and holding means may be used with any type of firearm.

Other of the objects of the invention will appear from the following description and disclosure.

In the drawings:

Fig. 1 is a fragmentary side elevation with portions thereof in section.

Fig. 2 is a fragmentary view of the breech bolt and slide in locked position, with portions thereof in section.

Fig. 3 is similar to Fig. 2 with the exception that the slide has been moved rearwardly and the breech bolt unlocked.

Fig. 4 is similar to Figs. 2 and 3 with the exception that the slide has been moved further to the rear and the bolt has been moved to the rear.

Fig. 5 is similar to Fig. 3 and shows a modification of the slide and the cam for the initial extraction lever.

Fig. 6 is a sectional view taken on line VI—VI of Fig. 1.

Fig. 7 is a view of the magazine looking towards its forward face with the latch shown in dotted lines.

Fig. 8 shows a magazine latch per se.

Fig. 9 is a fragmentary sectional view of the gun, said fore-end sliding on the guide tube 49

bolt and slide showing a lug on the firing pin for positive retraction of the firing pin.

Fig. 10 is a fragmentary enlarged section showing the magazine latch holding means and the front face of the magazine.

Fig. 11 is a fragmentary side elevation, to a larger scale, of the firing mechanism and magazine attachment shown in Fig. 1.

Referring to Figs. 1 and 11, the breech bolt 20 is carried by the action slide 21, a firing pin 22 having firing pin spring 23 (Fig. 4) being mounted in said breech bolt 20. Hammer 24 is pivoted at 25 and is adapted to strike the end of the firing pin 22 under the influence of main spring 26 acting through the hammer link 27. A trigger 28 pivoted at 29 has a sear 30 adapted to engage sear notch 31 of hammer 24 so that when trigger 28 is depressed the hammer will be propelled forward by the main spring 26. The action slide lock 32 is pivoted at 33 and is rotated about this pivot by a spring or wire 34 which slides in the slot 35 of the action slide lock 32, the other end of the spring 34 being fastened to the hammer link 27 and reciprocating therewith. When the hammer link is forward as shown in the full lines (Figs. 1 and 11), the end of spring 34, engaging slot 35, is forward of the pivot 33 and serves to rotate the action slide lock in a clockwise direction, removing the forward edge 32 of said lock from its blocking position back of the extension 36 of the slide 21. At a rearward portion 37 of the action slide lock there is a plunger 38 forced outwardly by a spring 39 which engages trigger lock 40, said trigger lock being pivoted at 41, and its lower end 42 being adapted to enter the notch 43 of trigger 28. When the trigger lock enters this notch, the trigger is held downward and cannot be actuated. The location of plunger 38 is such that when the forward end of the action slide lock 32 is in the unlocked or downward position, the plunger 38 will be in its upward position and above the center 41 of the trigger lock, and serve to rotate the trigger lock 40 in a counter-clockwise direction, tending to move the tip 42 in engagement with the trigger notch 43. As soon as the trigger is released or the portion 44 of the hammer 24 in its cocking movement contacts the extension 45 of the trigger and forces the trigger downwardly, tip 42 will enter notch 43. A suitable trigger spring 46 serves to rotate the trigger about its pivot 29 and a conventional cross lock 47 may be provided for locking the trigger. A fore-end or operating handle 48 is provided for the operating of the gun, said fore-end sliding on the guide tube 49

and having attached thereto the action slide operating bar 50. When it is desired to open the bolt, the fore-end is moved rearwardly on the guide tube 49, motion thereof being transmitted through bar 50 to the action slide 21. The slide may be moved rearwardly if the hammer is in the fired position because the action slide lock 32 has been moved to unlocked position, the spring 34 having been carried ahead of pivot 33 by the hammer link 27, thereby rotating the lock in a clockwise direction. In the event that it is desired to open the action while the hammer is cocked, a finger piece 51 is provided which is integral with the action slide lock 32 and which when depressed moves the lock 32 to the unlocked position. Further movement of the slide rearwardly, resulting from movement of the operating handle, occurs until the slide passes over the pad or extension 52 of the trigger lock 40 which serves to positively move the trigger lock into locking position because of engagement of portion 44 which extension 45, thereby causing tip 42 to enter notch 43. As the action slide is moved forward, it can be seen that the action lock 32 is held downwardly by the slide 21, which in turn prevents the trigger lock from being moved into unlocked position until the action slide is all the way forward and the action lock 32 moves upwardly, thereby moving plunger 38 to a point below the trigger lock pivot 41. It is still necessary, however, to release trigger 28 and apply pressure thereto again before the gun may be fired, because as long as pressure is maintained on trigger 28, even though the action lock 32 is in locked position, the pressure exerted on tip 42 is sufficient to prevent the spring 38, which at this time may be below the pivot 41, from rotating the trigger lock 41 into unlocked position. The trigger lock 41, even though it is free to move upwardly by the reason of tip 36 clearing action slide lock 32, however, will not move upwardly into locking position until the trigger lock is released because the relation of parts is such that the spring 34 acting to the rear of pivot 33 will not rotate the slide lock until trigger lock 40 has been rotated to its released position. The pressure of spring 34, acting to the rearward of pivot 33, therefore, will be insufficient to rotate trigger lock 40 until pressure is released from the trigger 28. The receiver 53 is provided with a locking notch 54 which receives the locking surface 55 of bolt 20. The bolt 20 is movably carried in the action slide 21, action slide 21 sliding in suitable grooves 56 (Fig. 6) in the receiver 53.

Referring now to Fig. 2, the bolt is shown in its locked position wherein the locking surface 55 is engaged with the locking notch 54 of the receiver. The bolt is held in this locking position by the cam 57, which is part of the slide 21, there being, if desired, one on each side of the slide. The cam 57 engages the lug 58 located on the bolt, which holds the bolt in the upper position, there being a lug 58 on each side of the bolt. When the slide 21 is moved rearwardly as the fore-end is operated, a cam 59, one of which may be located on each side of the slide, engages the lower rearward tip of lug 58 of the bolt and causes the bolt to be withdrawn out of the locking notch 54 (Fig. 3). The clearance below cam 59 is such as to allow passage of lug 58 as movement of the slide is continued, as in Fig. 4, the lugs and cams not being shown therein. Due to the expansion of the cartridge case or shell upon firing, it is often difficult to start or disengage the same in the initial extraction movement. An extractor

60 engages the rim of the shell and serves to move the shell rearwardly with the bolt. In order to aid the initial movement of the shell and bolt to the rear, a member 61 is pivoted at 62 in the bolt 20 (Figs. 3 to 6). The lower end of this member may be bifurcated to straddle lug 63. The upper end of member 61 engages a recess 64 in the inside of the top surface of receiver 53. The lower end of member 61 is engaged by the cam slots 65 located on the top surface of slide 21. The lug 63 at the end of the relative movement of the slide 21 to the bolt 20 is adapted to engage or abut against the shoulder 66 so that the slide and bolt will move rearwardly together under the motion imparted thereto by the fore-end 48.

Referring now to Fig. 2, the bolt and slide are in their locked and forward position in which the gun is ready to be fired or has been fired, the forward tip 67 of slide 21 engaging the lower portion 68 of bolt 20 holding the bolt in locked position. As the fore-end 48 is moved rearwardly, motion thereof is transmitted through bar 50 to action slide 21, the slide 21 then moving relative to bolt 20, drawing lug 58 downwardly by cam 59 as the lug 58 is disengaged from cam 57. At this time, the cam surface 65 has changed its relation to member 61 such that a force is applied to member 61 in a clockwise direction and, as the bolt is unlocked, further movement of the slide relative to the bolt will put additional force on the tip 61, acting against the recess 64 serving to perform an initial slow and powerful extraction operation, tending to loosen the cartridge case so that it may be moved rearwardly. This action continues until, as in Fig. 4, the lug 63 has engaged surface 66, whereupon the movement of the fore-end will be directly applied to the bolt and the slide together, and the bolt will move at the same rate as the operating handle and slide and without multiplication of the force applied, whereas previous to this the rate was slow and depended upon the relative movement of the bolt and slide acting on member 61.

The action of the cam in the slide on member 61 may also be employed to force the bolt home in the closing operation. The cam 69 may have its rearward surface 70 (Fig. 5) so designed and the recess 71 so arranged that forward movement of the slide relative to the bolt after the bolt has reached its forward position will result in a rotation of 61 counter-clockwise, the upper tip engaging the rear surface of recess 71 and forcing the bolt forward with a slow and powerful movement. The firing pin spring normally is depended upon to retract the firing pin after the hammer is in cocked position or free from the rear end of the bolt. A lug 72 (Fig. 9) may be provided on the firing pin 22 such that it will be engaged by projection 63 as the slide moves rearwardly relative to the bolt, thereby pulling the firing pin to the rear and positively retracting the firing pin.

The cartridges are placed in a magazine 73 which may be inserted in the opening therefor in the lower part of the receiver. The magazine has a follower 91 and a suitable spring 90 forcing the follower upward and the cartridges into the path of the bolt for movement into the chamber in the usual manner. The magazine 73 is held in place by a retractable lug 74 at the rear end of the receiver opening, said lug being forced forward by a suitable spring and limited in its movement by screw 75. At the forward end of the receiver there is located a spring pressed latch 76 contained in a transverse opening in

receiver. The surface 77 (Figs. 1, 10 and 11) of the aperture in the receiver 92 is inclined inwardly and the contacting elements of the magazine have a similar slope. A lug 78 (Figs. 1, 7, and 11) is located on the forward surface of the magazine and has a notch 79 therein, the upper surface 80 of the lug 78 having a cam or inclined edge for the purpose which will appear presently. The latch 76 has a projection 81 for engagement with the notch 79, surface 82 being lined to engage with cam surface 80, so that the magazine is pushed into position the latch will be moved sidewardly until the notch 79 is reached, whereupon spring 83 will return the latch 76 to lock the magazine in place. The latch 76 is held in position by a projection 84 of button located in the opening 86 in the receiver, guide 49 being screwed or otherwise fastened into opening 86 and holding button 85 in place, which turn causes projection 84 to enter the slot 87 and limit the movement of latch 76. When the magazine is first caused to enter the aperture in the receiver the spring pressed lug 74 is depressed, allowing easy entrance of said magazine to the aperture until the lug 74 snaps into an opening 88 of the magazine and the lug 81 has entered the notch 79.

The embodiment of the invention illustrated in the drawing and described herein is typical and illustrative only, and it is evident that the invention is capable of embodiments in other forms, all falling within the scope of the appended claims, which are to be broadly construed. What is claimed is:

1. In a firearm having a receiver, a reciprocating slide and a breech bolt having a vertical slot therein, said breech bolt being carried by the slide and movable relative thereto; a member pivoted on the bolt and carried in said slot; an arcuate cam on the slide engaging one end of the member, said member being actuated in the rearward movement of said slide by engaging and averting said arcuate cam, the other end of the member operatively engaging the receiver; means on the slide adapted to enter the slot and limit the relative movement of the slide and bolt; a firing pin carried by the bolt, said firing pin having a depending lug entering the slot between the means on the slide and the rear end of the bolt; a reciprocating handle operatively connected to the slide whereby operation of the handle first causes movement of the slide relative to the bolt, said relative movement rotating the said member, which slowly moves the bolt relative to the receiver, the means on the slide thereafter engaging the lug on the firing pin which is moved rearwardly until it reaches the rear end of the slot, thus positively retracting the firing pin, further movement of the operating handle moving the bolt and slide rearwardly together.
2. In a firearm, a barrel; an operating handle; guide means for said operating handle; a receiver carrying said barrel and guide means; a cartridge magazine, said receiver having an aper-

ture adapted to receive said cartridge magazine; a transversely movable spring pressed latch having an elongated longitudinal slot therein, said latch being mounted in said receiver between the magazine and the guide means and adapted to releasably hold the magazine in place; a member with a projection thereon which enters the slot in the latch to prevent transverse removal of the latch from the receiver, said last named member being held in position by the guide means.

3. In a firearm, a box magazine having side and end walls, one end wall of the magazine sloping upwardly and inwardly toward the other end wall of the magazine; a receiver having an aperture therein adapted to receive and substantially conforming to the configuration of the magazine; a transversely movable spring pressed latch mounted in the receiver adjacent to and adapted to engage a lug on the inwardly sloping face of the magazine, said latch and lug having cooperating cam surfaces so that the latch will be moved transversely as the magazine is inserted in place, the opposite end wall of the magazine having an aperture; a spring pressed lug in the receiver adapted to engage the said last mentioned aperture when the magazine is in place and yieldable as the magazine is inserted into place.

4. In a firearm having a receiver, a reciprocating slide and a breech bolt carried on said slide and movable relative thereto; a member pivoted on the bolt comprising a lever sharply rounded at its extreme lower end; said slide having an arcuate concave slot therein adapted to be engaged by the rounded end of the lever; said receiver having a recess on the opposite side of the breech bolt from the slot in the slide, said recess being adapted to be engaged by the other end of the lever, said slot, recess and lever lying substantially in a plane normal to the direction of reciprocation of the breech bolt and slide when the latter are in their forward position, whereby the effective length of the lever and the resulting leverage force imposed upon the breech bolt by the initial rearward movement of the slide is maximum and substantially constant during primary extraction; a reciprocating handle operatively connected to the slide whereby initial rearward movement of the operating handle causes movement of the slide relative to the bolt and said relative movement between the slide and bolt causes rotation of the pivoted lever member and a slow retraction of the bolt, and thereafter upon the completion of said relative movement the slide carries the bolt rearwardly directly with the movement of the operating handle, and upon return movement of the operating handle the relative movement between the slide and bolt after the bolt has reached its forward position re-engages the two ends of the lever with the slot and recess and serves to rotate the lever in the opposite direction, thereby exerting maximum leverage for forcing the bolt forward.

CHARLES H. BARNES.
